UNITED STATES PATENT OFFICE.

EZEKIEL H. SEFERIAN, OF COLUMBUS, OHIO.

SCRUBBING-MACHINE.

No. 906,069.

Specification of Letters Patent.

Patented Dec. 8, 1908.

Application filed June 30, 1908. Serial No. 441,184.

To all whom it may concern:

Be it known that I, EZEKIEL H. SEFERIAN, a citizen of the United States, residing at Columbus, in the county of Franklin and State of Ohio, have invented a new and useful Scrubbing-Machine, of which the following is a specification.

This invention relates to scrubbing machines and its object is to provide a device of this character which is of simple and durable construction and which is designed to be pushed over the surface to be scrubbed, this action sufficing to reciprocate a brush carried by the machine. The movements of the brush and the body of the machine are so proportioned that when said machine is propelled in one direction the brush in spite of its reciprocation moves only in one direction relative to the surface thereunder.

Another object is to provide a brush which can be readily attached to the machine and which has means for maintaining it in contact with the surface thereunder, said means being disposed to automatically take up wear upon the brush.

A further object is to provide simple mechanism for actuating the brush.

With these and other objects in view the invention consists of certain novel features of construction and combinations of parts which will be hereinafter more fully described and pointed out in the claims.

In the accompanying drawings is shown the preferred form of the invention.

In said drawings: Figure 1 is a plan view of a scrubbing machine constructed in accordance with the present invention, the handle being removed. Fig. 2 is a section on line A—B, Fig. 1, and showing a portion of the handle in elevation. Fig. 3 is a section on line C—D, Fig. 1. Fig. 4 is a plan view of a modified form of machine, a portion thereof being broken away. Fig. 5 is a section on line E—F, Fig. 4.

Referring to the figures by characters of reference, 1, 1 designate the side members of the frame of the machine each of said members having a longitudinal guide groove 2 in its inner face and each of said members also has upstanding portions 3 to which are connected parallel cross bars 4. Journaled within the end portions of the side members 1 are parallel shafts 5 and 6, said shafts rotating within the members 1 and the shaft 5 being provided at its ends with wheels 7. Shaft 6 is provided with preferably two

cranks 8, 8 located between but adjacent the members 1 and mounted upon each of these cranks is a pitman 9 pivotally engaging one of the cross bars 10 of a carriage A. This carriage consists preferably of two bars 10 in parallel relation and having their ends mounted to slide within the grooves 2, and arranged upon each of the bars 10 are posts 11 to which are secured connecting strips 12 which serve to hold the bars 10 properly spaced apart at all times.

A backing plate 13 is arranged between the bars 10 and has oppositely extending arms 14 which are slidably mounted on the posts 11, said arms being held normally pressed upon the bars 10 by means of springs 15 mounted on and bearing at their ends against strips 12 and arms 14 respectively. Openings 16 are formed within plate 13 and are designed to receive bolts 17 extending through the back of a brush B. Any suitable means such as wing nuts 18 may be mounted on the bolts 17 for clamping the brush against the plate 13, and if desired, a filling strip 19 of any suitable material may be interposed between the brush and plate. Recesses 20 are formed in the outer faces of the side members 1 adjacent the centers thereof and are designed to be pivotally engaged by the ends of a handle 21 which may be of the construction employed with ordinary carpet sweepers and similar devices.

It is of course to be understood that the shaft 6 is provided with wheels 7 similar to those upon the shaft 5. The cranks 8 are of a length substantially equal to the radius of each of these wheels so that the stroke of the pitman 9 are substantially equal to the diameter of each wheel 7.

In using the machine herein described the same is moved in either direction by means of the handle 21. During one-half the rotation of the shaft 6 cranks 8 will drive the carriage A in the same direction in which the machine is moving and therefore a forward brushing action will be produced. During the other half of the rotation of shaft 6 the carriage A will be drawn in a direction opposite to that in which the machine is moving and at approximately the same speed so that the brush will thus remain practically stationary relative to the surface being cleaned during this movement. It will be apparent therefore that during one continuous movement of the machine in one direction an intermittent forward brushing

action will be produced. As the brush wears as a result of constant use the springs 11 will press the plate 13 downward, thus automatically taking up the wear and at the same time hold the brush firmly in contact with the surface thereunder. When it is desired to remove the brush and substitute a new one it is merely necessary to unfasten the bolt 17. It will be seen that the device 10 is very simple, durable and efficient and can be conveniently manipulated.

When it is desired to utilize a machine in which the brush rapidly reciprocates a construction such as illustrated in Figs. 4 and 5 15 may be utilized. By referring to these figures it will be seen that two of the supporting wheels 22 thereof are secured to the shaft 23 having gears 24 upon the end portions thereof, these gears meshing with smaller gears 25 carried by a shaft 26 on which a larger gear 27 is also mounted. Gear 27 meshes with an idler gear 28 which in turn drives a gear 29 secured to a shaft 30, which shaft has cranks 31 which drive pitmen 32 corresponding to the pitmen 9 heretofore referred to. A suitable housing 33 is preferably arranged upon each side of the frame 34 so as to conceal and protect the train of gears located at each side of the 30 frame. When a machine of this construction is pushed over a floor or other smooth surface the shaft 30 will be revolved at a high speed relative to the driving wheels 22 and the brush 35 carried by the machine 35 will be rapidly reciprocated.

What is claimed is:

1. A machine of the character described comprising a wheel-supported frame, a carriage mounted to reciprocate therein, and

having posts extending upwardly from the 40 corners thereof and connections between the upper ends of the posts, a backing plate slidably mounted on the posts, springs upon the posts and bearing at opposite ends against the said connections and the backing plate respectively, a brush movably mounted within the frame, a filling strip interposed between and secured to the back of the brush and the backing plate, and means actuated by one of the wheels for reciprocating the carriage. 50

2. In a machine of the character described the combination of a wheel-supported frame having longitudinal guide grooves set in opposite portions thereof, a carriage mounted to reciprocate within the 55 frame, the ends of the carriage being mounted within the grooves, said carriage having corner posts upstanding therefrom and connecting strips secured thereto, a backing plate mounted to slide upon the corner posts, 60 springs upon said posts and interposed between and bearing against the connecting strips and the backing plate, a brush movably mounted in and extending below the carriage, a filling strip interposed between 65 the back of the brush and the backing plate, means for securing the back of the brush, the filling strip and the backing plate detachably together, and means operated by the movement of the frame for reciprocating the carriage. 70

In testimony that I claim the foregoing as my own, I have hereto affixed my signature in the presence of two witnesses.

EZEKIEL H. SEFERIAN.
